(57) **CLAIM**

The ornamental design for a loudspeaker as shown and described.

DESCRIPTION

The file of this patent contains at least one drawing/photograph executed in color. Copies of this patent with color drawing(s)/photograph.

1. Loudspeaker
- 1.1 : Perspective
- 1.2 : Front
- 1.3 : Back
- 1.4 : Left
- 1.5 : Right
- 1.6 : Top
- 1.7 : Bottom

The present design of the loudspeaker is characterized by materials such as metal, wood, and synthetic resin.

The broken lines in the drawings are for illustrative purposes only and form no part of the claimed design. Everything within the white broken lines is not claimed.

1 Claim, 7 Drawing Sheets
(7 of 7 Drawing Sheet(s) Filed in Color)
